Primary Examiner — David Muller(74) Attorney, Agent, or Firm — Stetina Brunda Garred & Brucker(57) CLAIM

The ornamental design for a pedicure spa platform, as shown and described.

DESCRIPTION

FIG. 1 is a front perspective view of the pedicure spa platform of the present invention showing my new design;

FIG. 2 is a side elevational view thereof;

FIG. 3 is a top plan view thereof;

FIG. 4 is a front end view thereof;

FIG. 5 is a rear end view thereof; and,

FIG. 6 is a bottom plan view thereof.

The broken line showing of parts of the drawings is included for the purpose of illustrating use and environment and forms no part of the claimed design.
